APPARATUS FOR EXTRACTING GELATIN
AND GLUE

William V. Knoll, Dayton, Ohio

Application June 29, 1938, Serial No. 216,548

7 Claims. (CL 210—150.5)

This invention relates particularly to an apparatus for liberating gelatin and grease from animal matter such as hides and hide trimmings, sheep pates, bones, horn piths, etc., but is applicable also in the reduction of fishery offal, and in the liberation and separation of oils and other by-products from vegetable matter such as soy beans, castor beans, nuts, and kindred vegetable growth.

10 In the manufacture of gelatin and glue, its liberation from the aforesaid raw materials is accomplished by cooking the materials, which have previously been washed and treated, in water at a comparatively low temperature, and while this operation is known in the industry as the boiling operation, the temperature at which it is carried out is seldom as high as the boiling point of water ranging instead from one hundred thirty to two hundred degrees Fahrenheit.

15 20 In the preparation of these raw materials for the boiling operation, particularly the hides and trimmings, it is the conventional practice to place the materials into pits or concrete tanks, where a cover of approximately a two percent milk of lime solution is applied and left on for a period of four to twelve weeks. Where packer's salted hide trimmings are being prepared, they are given a preliminary washing to remove dirt and salt, before being placed in the liming pit.

25 30 Bone is given a preliminary treatment which comprises crushing and degreasing and subsequent maceration for extraction of the mineral substance by means of diluted acid, thereby producing a by-product acid phosphate.

35 To shorten the time of preparation for the boiling operation, the more drastic method of applying caustic soda is sometimes employed, but when this chemical is used, great care and attention must be given to prevent overtreatment.

40 45 In any event, after the stock has been properly limed, which may be in some degree evidenced by the swollen condition of the material, it is removed from the liming pit and placed in open washers, such washers generally comprising round wooden tanks set into a wash room floor. Usually a cone shaped roller is attached to a vertical post in the center of the tank and made to roll in a circular path over the top of the stock being washed, squeezing and rubbing out the lime.

50 The washing operation requires from ten to seventeen hours, until a titration test indicates that the alkalinity of the wash water has been reduced to a factor of 0.1. At this point, sulphuric acid is added to the stock as a neutralizer,

and after being subjected to the acid treatment for a period of as long as eight hours, the stock is again washed until it is but slightly on the acid side. This completes the preparation for the boiling operation.

5 While a number of improved devices have been proposed to facilitate the boiling operation, the industry in general still employs rather crude apparatus for this purpose. The most commonly employed apparatus comprises an open wooden vat having a steam coil resting on the bottom. In some cases heat is transferred to the material being cooked by allowing steam to escape through small leakage holes in the steam pipes and percolate through the mass.

10 15 More generally the steam coils are not provided with leakage holes but transfer the heat of the steam to the mass by conduction. In such cases the coils are covered by a layer of excelsior which is in turn covered by a plank floor upon which the mass of material rests. The floor is provided with cracks or perforations to permit circulation of the liquor about the coils.

20 25 The space in the vat above the floor is substantially filled with the prepared animal matter, enough soft water being added to cover the stock. Steam is then turned into the heating coils to bring the water to the desired temperature, which depends somewhat on the kind of material being treated.

30 35 Obviously, with a heating element at the bottom of an open top vat it is very difficult to maintain a uniform temperature through so large a mass, although the maintaining of a uniform temperature is highly important in the production of a high quality product.

40 In these open type vats no means of agitation is provided, the operators merely loosening up the mass at intervals by inserting long hand paddles whereby they lift a portion of the mass near the bottom to the top and open up spaces into which the warm liquor may penetrate. This means of agitation is slow and laborious and rarely loosens up the mass uniformly, and consequently many parts of the material remain for hours before being reached by the heated liquor, whereby the boiling operation is greatly prolonged.

45 50 Certain grades of skins, such as sheep pates for instance, may contain up to 22% of their dry weight in soluble fat or tallow. Due to the low temperatures used, this fat is released slowly and rises to the top in small quantities during the entire cooking period, where it must be 55

skimmed at frequent intervals by the operators, with hand scoops.

Due, however, to the unequal heating, and to the prolonged period required for the hot liquor to reach all parts of the mass, the liberation of the fat is imperfectly accomplished so that, after the cooking period is entirely completed, the mass still contains a large percentage of the available grease or tallow, which is customarily removed in a filter press, or by subjecting the mass to a gasoline extraction process. Even after use of a filter press there usually remains in the stock from six to nine percent of the grease.

Obviously, with the use of the open vat used as above described, or any other equipment at present employed in the art, the cooking period is greatly prolonged, the labor involved considerably greater than it should be and the final results far from as effective as desirable. Further, the prolonged period for which a given volume of material must be cooked necessitates a large number of vats which necessarily require a large floor space area.

The period required to dispose of a single vat full of stock is further prolonged because the residue, from which the liquor has been extracted, settles to the bottom and is then removed with shovels or forks, the vat being subsequently cleaned of the excelsior and solid matter then thoroughly washed before it may be used again. Several hours are added to the time consumed by these cleaning operations.

With certain kinds of gelatin or glue stock, it has been found unadvisable to liberate all of the available gelatin, glue and tallow in a single cooking operation. This is due to the fact that the lower the temperature maintained in the circulating liquor, the higher the quality of the gelatin reclaimed. Such low temperatures, however, do not liberate a very high percentage of the total available gelatin, with the result that treatment at higher temperatures must follow if substantially all of the available gelatin is to be extracted.

These stocks are usually subjected to several cookings, fresh water being introduced in each instance. The liquors drawn off in the several cookings are designated as first run, second run, third run, and fourth run liquors the temperature being raised at each succeeding run a matter of 10 or more degrees. It is of course the aim of the manufacturer to recover as much of the available gelatin in the first cooking as possible, because the first run liquor will produce a product of the highest quality and of the greatest market value. Gelatin produced from second, third and fourth run liquors is of progressively darker shade and lower quality. Glue from these subsequent runs is of lower adhesive quality as well as of less transparency than that made from first run liquor.

It is therefore the practice to prolong the first or low cooking period, not necessarily for a fixed period of time, but long enough to allow the liquor to reach a density usually corresponding to four to six percent of the dry gelatin, whereupon the liquor is drawn off and subsequently treated in an evaporator to further reduce it to a density of approximately ten percent of the dry product.

The treatment in an evaporator is, however, generally admitted to be detrimental to the color and quality of the product and therefore any method or apparatus which would reduce the liquor of the first cooking to a density sufficient to warrant elimination of the subsequent evap-

orating operation, and do this in a greatly reduced period of time, with less labor and equipment and in less floor space, would be a valuable contribution to the art.

It is therefore an object of this invention to provide an apparatus which will greatly reduce the time consumed, the steam used, the labor expended, the amount of equipment needed and the floor space required, for liberating a given amount of gelatin from a given quantity of stock.

Another object is to provide an apparatus which will liberate and remove substantially all of the grease content in the stock being treated, whereby subsequent pressing of the residue or subsequent gasoline treatment following the boiling operation is unnecessary.

Another object is to provide an apparatus whereby the heat necessary to the boiling operation and glue liberation may be made to quickly reach every part of the mass of stock and be kept uniform throughout the cooking period, to the end that liberation of first run liquor may be complete in all parts of the mass at the same time and in the shortest possible period.

Another object is to provide means for removing a greater percentage of the available gelatin in the first cooking period, whereby more of the better quality gelatin will be produced from a given volume of stock.

A further object is to provide means for producing a more highly concentrated liquor in a given time and with a given temperature, to the end that a separate evaporating operation may be avoided and the produce thereby benefited.

Still another object is to provide apparatus adapted to greatly facilitate the removal of the residue thereby saving considerable time and hard labor.

Other objects and meritorious features of the invention will become apparent from a consideration of the following description, reference being made to the drawings, wherein,

Fig. 1 is a front elevation of an apparatus for carrying out my invention.

Fig. 2 is an end view taken from the left of Fig. 1, showing more particularly the gear drive mechanism.

Fig. 3 is an end view taken from the right of Fig. 1 showing more particularly the water feed mechanism.

Fig. 4 is a top plan view of the apparatus.

Fig. 5 is a transverse section taken at 5-5 of Fig. 1, showing the agitating means, the charging manholes and the residue removal outlets.

Fig. 6 is a transverse section, taken at 6-6 of Fig. 1, showing the steam jacket structure.

Like numerals refer to like parts throughout the several views.

Construction

Referring now to the drawings which are illustrative of one embodiment of my invention, a stationary tank 10, having a bottom 12 of semi-circular transverse cross section, and end walls 14, is mounted on a plurality of short legs 16 which extend upwardly from a base 18.

The top of tank 10 is flanged outwardly as at 20 to facilitate making a low pressure joint with a transversely arcuate lid 22 having a similar flange 24. Flange 24 is adapted to rest on flange 20 and is secured thereto by bolts 26. A gasket (not shown) may be inserted between the two flanges as a precaution against leakage therebetween.

Secured to the outer curved surfaces of the tank bottom 12 by riveting, welding, or any similar means which will provide a steam tight joint, are a series of steam jackets 30 which together hold the steam for maintaining the desired temperature in the tank.

Longitudinally extending steam pipes 32 controlled by valves 34 join the several jackets. The steam pipes 32 may, of course, be connected to a common source of supply and controlled by a common steam supply valve if desired. Condensate drip pipes 36 extend longitudinally under the tank and may be controlled by suitable steam traps as in common practice. Any suitable temperature control device in commercial use may be selected and incorporated to maintain the desired temperature at a uniform value.

The short legs 16 have their upper surfaces contoured to fit the curved surfaces of the steam jackets.

Intermediate the steam jackets 30 in the tank bottom 12 are the residue removal chutes 38 provided at their outer ends with flanges 40 to which are secured the chute covers 42 by the screws 44. Drain cocks 45 are provided to facilitate removal of the liquid residue without removing the solid matter. Liquor draw off pipes 47 and 49, controlled by valves 51 and 53 enter the tank at a plurality of points. A conventional density responsive control valve (not shown) may be inserted in the line, said valve to open when the density of the liquor has reached a predetermined value.

At the extreme top in the lid 22 is formed a grease trap 46 which preferably may have a transparent panel or window 48 somewhere within its length, through which the contents in the trap may be observed. A grease draw-off pipe 50, controlled by valve 52, extends alongside said trap and communicates therewith at several points within its length as at 54, 54. A relief cock 55 is provided to permit air to escape when it is desired to completely fill the tank with water.

Mounted to be revolved within the tank 10 is the cylinder 56 having end heads 58 to the inner face of which the flanges 60 of the journals 62 and 64 are secured. Packing glands 66 in the tank end walls 14, allow the rotatable journals 62 and 64 to extend through and beyond the walls 14 without leakage. Bearings 68 and 70 are provided to rotatably support the journals, the bearings being supported on the stands 72 and 74 extending upwardly from the base 18.

A large distributing pipe 76 perforated as at 78 (see Fig. 1) extends throughout the length of the cylinder, the ends of the pipe extending a short way into the journals 62 and 64 to maintain a concentric relation between the pipe and cylinder.

Several channel shaped screens 80 of V shaped cross section and perforated as at 82 extend longitudinally at circumferentially spaced intervals along the inner wall of the cylinder, the open sides of the V being joined to the cylinder by welding or other suitable means.

A plurality of perforations 84 (see Fig. 5) extend through the several sections of the cylinder wall that are covered by the V shaped screens. Radial struts 86 and 87 may join the pipe 76 to the screens and cylinder, and, if provided, will perform the additional function of cutting through and loosening up the mass of stock as the cylinder revolves.

Longitudinally spaced manholes 88 extend through the cylinder wall and may preferably

be located circumferentially intermediate the V shaped screens, and should be longitudinally positioned in the same axially-transverse plane as the residue removal chutes 38. Drain plates 90 and 92 may preferably be welded to the cylinder wall 5 and should slope downwardly toward the man holes when the man holes are turned to the bottom over the chutes. Man hole covers 91 are secured over the man holes by the screws 93.

The journal 64 has a large central opening 94 10 extending throughout its length communicating at its inner end with the distributing pipe 76 and having at the outer end a rotatable sealing joint comprising a non-rotatable housing 96 with cover 98 into which the water supply pipe 100 15 extends. Screws 102 secure the cover to the housing.

Within the housing 96, a spherically faced collar 104 is press fitted to the journal 64 and a second spherically faced collar 106 is splinedly 20 mounted onto the journal so as to be axially slidable thereon.

The spring 108 urges the collar 106 axially toward the outer end of the journal. Two washers 110 have spherical faces ground for a pressure tight joint with the spherical faces of the collars, whereby water under pressure may be fed to the cylinder while it is under rotation. A valve 112 is provided to control the water supply.

To the outer end of the journal 62 there is 30 secured a sprocket 114 for rotating the cylinder. An electric motor 116 or other suitable power source is mounted on a cross member 118 of base 18. A speed reducing gear box 120 has its shaft 122 connected directly to the motor shaft 35 124. The outer end of the gear box shaft 122 has secured thereto the sprocket 126.

A countershaft 128 rotatably supported in bearings 130 secured to the sides of stands 132 and 12 by screws 134, carries the sprockets 136 and 138 the tooth pitch of which matches that of sprockets 126 and 114 respectively. Silent chains 140 and 142 drivably join the pairs of sprockets. The combined reduction through the chain drives and gear box provide a great reduction in speed 45 for the cylinder relative to that of the motor.

Operation

Where the per diem volume of stock which it is desired to treat is limited, a single apparatus as hereinbefore described may serve to carry out the liming, washing, and acidulating as well as the boiling operation. It may be preferable, however, where the production volume justifies, to employ the hereinbefore described apparatus for carrying out the boiling operation only, and then providing a separate apparatus for the other operations, such separate apparatus being somewhat modified to better effect that particular purpose.

Where the herein described apparatus is employed for liming, the operation is begun by removing the lid 22 and manhole covers 91 and filling the cylinder with the stock to be treated when replacing the man hole covers and lid and opening the relief cock 55. Water carrying about two percent lime in solution is then injected through the pipe 100 until the cylinder and all additional spaces within the tank 10 are completely filled. Water coming out at the cock 55 70 will show when the tank is full. The cock 55 is then closed and the cylinder kept rotating for about sixty hours, no steam being turned into the steam jackets after which the lime solution may be drawn off by the drain cocks 45. Obviously, 75

the constant rotation of the cylinder and the rubbing action through the mass by the screens 80 and the struts 86 soon applies the lime solution to every part of the mass of stock. When it is recalled that as much as ninety days is sometimes required to complete the liming operation by conventional methods it is apparent that the time saved by using the present apparatus is considerable.

10 The washing operation may be carried out by first closing the drain cocks 45 and opening the relief cock 55, then introducing clean soft water by way of the pipe 100 through the perforated distributing pipe 76 until the cylinder is completely filled. The relief cock is closed and, after the cylinder has been rotated for about one hour, the drain cocks are opened while the cylinder is kept rotating for a further period with a constant flow of water in at the pipe 100 and out 15 through the drain cocks 45, rotation of the cylinder and flow of the water being continued until a titration test shows the alkalinity of the water to have been reduced to a factor of 0.1. Sulphuric acid is now introduced through the incoming water to neutralize the stock, the period being extended until the stock shows slightly on the acid side whereupon all water is drawn off. No steam is introduced during the washing and acidulating operation, and fresh cold water only 20 is passed through the apparatus.

The boiling operation for which the apparatus is most particularly intended is preferably conducted as follows: With the cylinder substantially full of the limed, washed and acidulated stock, the man hole covers and residue chute covers securely bolted, the drain cocks closed and the relief cock open, fresh soft water, preferably at a temperature somewhat below the desired cooking temperature, is brought in through 25 the pipe 100 and into the cylinder through the perforations in the distributing pipe 76 until the relief cock shows full whereupon the relief cock is closed. Steam at the desired temperature for first run boiling is then introduced into the jacks 30 through the pipes 32, the regulator provided being set to the temperature most suitable for the stock being treated. Power is now applied 35 to rotate the cylinder.

As the stock is turned over and over within 40 the cylinder, the temperature of the liquid rises and begins to release the grease or tallow from the stock permitting it to flow up into the grease trap where it accumulates until the operators see it through window 48 and draw it off through 45 pipe 50, by opening valve 52. The grease or tallow will continue to be thus liberated as long as any remains in the stock capable of being broken down by the temperature being applied. It is desirable to remove the grease or tallow from 50 the gelatin liquor at the earliest possible moment.

When it is considered that there may be as much as several tons of stock in the cylinder at one time, it is obvious that, during cylinder rotation, the stock is continuously, by its own weight, being pressed against, and rubbed over, the V shaped screens, whereby the liberated products are forced into the V channels and out of the cylinder through the holes 84. During this 55 time the struts 86 constantly pass through the mass and assist its movement in a manner to help the liquid to penetrate all parts thereof. Obviously this treatment will produce a highly concentrated gelatin bearing liquor in the space in 60 the tank outside the cylinder in a much shorter

time than when conventional boiling methods are followed.

If the apparatus has been provided with conventional automatic density control mechanism as hereinbefore suggested, the boiling operation 5 for producing first, second, third, and fourth run liquors may be continuous.

With such a valve no withdrawal of gelatin bearing liquor will occur through pipes 47 until the boiling operation has proceeded far enough 10 to produce the desired concentration for first run liquor whereupon the valve will open automatically and allow liquor to discharge and fresh water to follow in through pipe 100 until the density is lowered sufficiently to close the valve. 15

The steam control is next set for a higher value to liberate the gelatin for second run liquor. When the density again reaches the desired value the automatic valve will draw off the second run liquor, the same process of raising the heat in 20 the steam jackets being subsequently repeated until all of the gelatin has been extracted as third run, fourth run, etc. Of course, the tests for density may be made manually and the valve 25 51 or 53 or the cock 45 hand operated when the desired density has been reached to draw off the liquor, each run being made with fresh water and higher heat.

When all the grease and gelatin has been removed, the residue must be removed. This will 30 best be accomplished by first removing the lid 22 then removing the man hole covers 91 and the chute covers 42 then revolving the cylinder with the man holes open. Part of the residue will be deposited in the chutes at each revolution and 35 may be helped out of the chutes with a rake. When substantially all of the residue has been dumped into the chutes, the cylinder is stopped with the man holes over the chute openings and the cylinder may be thoroughly cleaned by injecting clean hot water through the perforated 40 distributing pipe 76.

Inasmuch as the raw stock is confined in the cylinder and slowly but uniformly agitated and 45 pressed and rubbed against the screens while under heat, rapid and thorough extraction of the gelatin and grease is effected, and because of the uniformity in the application of the heated liquor to the stock a greater volume of first run liquor is produced. The filling of the cylinder 50 and the discharge of the residue is also facilitated by the peculiar construction of the apparatus.

Standard practice may be followed in some 55 of the subsequent steps in completing the process of making gelatin and glue, that is, the introduction of filters to clarify the liquor, subsequent operations to further concentrate the same, molding, gelling, drying, grinding, etc., these steps forming no part of the invention are not further described.

While a single embodiment of the invention 60 has been disclosed to illustrate the principle thereof it will be understood that various modifications and exemplifications will come within the scope of the following claims.

I claim:

1. The combination, in apparatus of the character described, of a tank, an axially-horizontal hollow cylinder rotatable in said tank, circumferentially spaced longitudinally extending channel shaped screens within said cylinder having their open sides secured to the cylinder walls, said cylinder wall being perforated in those portions embraced by the said open sides, and a distributing pipe coaxial with said cylinder ex- 75

tending lengthwise therethrough and having axial perforations throughout its length.

2. The combination, in apparatus of the character described, of a tank, a horizontal hollow cylinder rotatable in said tank, circumferentially spaced longitudinally extending channel shaped screens within said cylinder having the open sides secured to the cylinder walls, said cylinder walls being perforated in that portion covered by said channels, a coaxial perforated distributing pipe extending through the cylinder and supported in its end walls and a series of struts having one end secured to the pipe and the other end to the bottoms of said channel screens.

15 3. Apparatus of the character described, comprising, in combination, a tank, a relatively close fitting cylinder rotatable within said tank, a coaxial perforated distributing pipe extending lengthwise through said cylinder, circumferentially spaced longitudinally extending channelled screens projecting from the cylinder walls inwardly, said cylinder wall having perforations under said screens, covers secured over longitudinally spaced manholes in said cylinder wall between said screens, and other covers secured over residue discharge openings in the bottom of said tank located in the same axially-transverse plane as said manholes.

4. Apparatus of the character described, comprising, in combination, a tank, a close fitting cylinder rotatably supported in said tank, a coaxial perforated distributing pipe extending lengthwise through said cylinder, circumferentially spaced longitudinally extending channel shaped screens projecting from the cylinder wall inwardly, said cylinder wall having small perforations under said screens, bracing members extending from said distributing pipe radially to said screens, said cylinder having large stock 40 filler openings in its wall and said tank having large residue discharge openings in its bottom in the same axially-transverse plane as the filler openings.

5. In a gelatin cooker, a tank, means for applying heat to the contents of said tank, a horizontally disposed cylinder revolvable in said tank, said cylinder having circumferentially spaced longitudinally extending rows of perforations in its walls, perforated channels secured to the inside of said walls over said rows of perforations for agitating the cylinder contents, a perforated distributing pipe centrally disposed within said cylinder, said cylinder having large filler openings in its walls and said tank having large discharge openings in its bottom adapted to communicate with said filler openings when they are turned toward the bottom, a grease trap in

the top of the tank, grease draw off pipes extending from said trap, and a series of gelatin draw off pipes in the side of the tank at different heights from the bottom.

6. In a gelatin cooker, a tank, a steam jacket 5 for applying steam to heat said tank, a horizontal cylinder revolvable within said tank and fitting it relatively closely, perforated agitating members of V shaped cross section extending longitudinally along the inner walls of said cylinder at circumferentially spaced intervals with the open side of the V section secured to the wall to rotate therewith, said cylinder having perforations under said members, a coaxial perforated distributing pipe anchored in the cylinder ends, 10 radially extending agitating members joining the perforated distributing pipe and the perforated agitating members, manhole covers longitudinally spaced in the sides of the cylinder, residue discharge covers diametrically opposite the manhole 15 covers and longitudinally spaced in the bottom of the tank, a grease trap in the top of the tank, grease draw off means extending from said trap, and gelatin draw off means located at intervals 20 in the sides of the tank. 25

7. A gelatin cooker comprising, in combination, a tank, a steam jacket against the wall of said tank, a horizontal cylinder rotatable in said tank, journals at the ends of said cylinder, one journal having an axial opening therethrough, 30 power means secured to the other journal to rotate said cylinder, a perforated distributing pipe within said cylinder coaxial with said cylinder and having its ends anchored in the cylinder ends, the one end communicating with the axial opening through said journal, a rotatable seal joint connecting the outer end of said journal to a stationary supply pipe to effect communication between said supply pipe and the axial opening through said journal, a series of circumferentially spaced longitudinally extending 35 perforated channel members having the open sides of the channels secured to the cylinder walls, said cylinder walls being perforated in the spaces embraced by said channels, agitating struts 40 extending from the distributing pipe to the channels and to the cylinder walls, manhole covers secured over manholes longitudinally spaced in said cylinder between said channels, laterally extending chutes in the bottom of the tank in the 45 same axially transverse plane as the manholes, a grease trap in the top of the tank, grease draw off means extending from said trap, and gelatin draw off means at different heights in the sides 50 of the tank. 55

WILLIAM V. KNOLL.
